INVENTOR

Edward H. Angle,

BY *Clifton C. Hallowell*

ATTORNEY

UNITED STATES PATENT OFFICE.

EDWARD H. ANGLE, OF NEW LONDON, CONNECTICUT.

ORTHODONTIC APPLIANCE.

1,204,114.

Specification of Letters Patent. Patented Nov. 7, 1916.

Application filed August 2, 1915. Serial No. 43,134.

To all whom it may concern:

Be it known that I, EDWARD H. ANGLE, a citizen of the United States, and a resident of New London, in the county of New London, State of Connecticut, have invented 5 certain new and useful Improvements in Orthodontic Appliances, of which the following is a specification, reference being had to the accompanying drawings.

10 My invention relates particularly to tooth-bands which serve as a medium of attachment between the arch-bar of a regulating device and the teeth of the dental arch, and is directed especially to the structure of the 15 band proper.

The principal object of my invention is to provide a tooth-band which is so reinforced as to afford ample rigidity when connected with the arch-bar of a tooth-regulating 20 appliance, to prevent distortion of the band, and to insure positive response of the tooth to the action of the arch-bar.

Other objects of my invention are to provide a tooth-band which may be so engaged 25 with the arch-bar that said arch-bar may be disposed in a plane as near the axis of said tooth-band as is practicable.

My invention also includes all of the 30 various novel features of construction and arrangement hereinafter more definitely specified.

In the accompanying drawings, Figure 1 is a perspective view of a tooth-band conveniently constructed in accordance with my 35 invention; Fig. 2 is a plan view of the tooth-band shown in Fig. 1, showing the arch-bar in operative engagement therewith; and Fig. 3 is an inverted plan view of the tooth-band shown in Figs. 1 and 2 before being formed 40 around the tooth.

In said figures, the tooth-band 5 is provided with a projection forming a hook 6 whose outer free extension 7 projects toward one edge of the tooth-band 5 and between 45 which and the tooth-band is a recess 8 in which the arch-bar 9 may be engaged.

The arch-bar 9, as best shown in Fig. 2, is preferably held in direct tangential contact with the tooth-band 5, and is prevented

from accidental displacement from the recess 8 by any suitable form of key or retaining device (not shown), which may extend through the aperture 10 in said projection, and be so formed as to lock said arch-bar 9 in the position shown in dot and dash lines 55 in Fig. 1.

The tooth-band 5 may be formed of a strip of metal or other suitable material, such as shown in plan or edge view in Fig. 3, which may be bent to conform to any selected tooth of the dental arch, and may have its ends joined in any suitable manner, such as shown, for instance, at 12 in Figs. 1 and 2.

The hook 6 is preferably disposed at or near the medial region 13 of the tooth-band 65 5, or, in other words, substantially equi-distant from the opposite ends 15 and 16, and said medial region 13, as shown in each of the Figs. 1, 2 and 3, is relatively thicker 60 than the other portions of the tooth-band, 70 tapering from said thickened medial region 13 to the regions of minimum thickness at the respective ends 15 and 16.

It will be readily seen that a tooth-band thus thickened at the region of the attachment of the hook or other attaching means for engaging the arch-bar, not only provides for the desired rigidity between the said hook and band, but affords such an attachment for the base of the hook, that said hook may be so formed that its free extension 7 opposes the outer surface of the band, whereby the arch-bar may be held by said hook contiguous to the tooth-band proper, and coöperate directly therewith when adjusted to vary the position of the tooth to be operated upon.

It will be obvious that a tooth-band constructed in accordance with my invention affords such a connection between the arch-bar and the tooth to be operated upon, that a closer relation between the lingual axis of said tooth of said arch-bar is effected.

I do not desire to limit my invention to the precise details of construction and arrangement herein set forth, as it is obvious that various modifications may be made therein without departing from the essential

features of my invention as defined in the appended claims.

Having thus described my invention, I claim:

- 5 1. An orthodontic appliance comprising a tooth-band tapering from its medial region.
2. An orthodontic appliance comprising a tooth-band having means to engage an arch-bar, and having the portion adjacent to said

means relatively thicker than the remainder 10 of said band.

In witness whereof, I have hereunto set my hand this 3rd day of July, 1915.

EDWARD H. ANGLE.
